HEALTH LAMP

Louis B. Modell, Great Neck, N. Y.

Application November 13, 1952, Serial No. 320,325

5 Claims. (Cl. 128—172.1)

1

This invention relates to new and useful improvements in health heat lamps.

More particularly, the present invention proposes the construction of a health heat lamp which may stay on all night or for any other prolonged period without overheating or causing injury to the occupants of the room in which it is being used and which will artificially reproduce atmospheric conditions of a desert in a defined area of a room.

Another object of the present invention proposes forming a health heat lamp in which the ultraviolet lamp can be completely baffled in the enclosure so that the rays cannot escape and burn the patient.

Still further, the present invention proposes constructing a health heat lamp having a stand or cabinet with a filter covered inlet opening and a motor and fan to draw in air and pass it through an ultraviolet field generated by an ultraviolet lamp, which sterilizes the air, and also serves to cool the tube, the stand or cabinet being connected with a reflector having an infrared element so that the filtered sterile air will pass by the infrared element and the rays and air stream will be directed in a common path.

As a further object, the present invention proposes arranging the filter, fan, ultraviolet lamp and infrared element so as to provide clean, dry sanitized air continually purged of aerial contaminants and especially beneficial for ill persons, such as those who suffer from sinus trouble, hay fever, asthma and upper respiratory discomforts, to induce restful sleep, particularly during the night when discomforts are most prevalent.

A still further object of the present invention proposes providing a medicant cup or container on the grill of the lamp disposed in front of the infrared heater element so that the infrared rays may help evaporate the medicant and the patient may sleep in a cone of filtered air, mildly medicated if desired, warmed and dehumidified, sterile and sanitized by ultraviolet rays without the creation of harmful nitrous oxide or ozone which is an irritant to asthmatics.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the health lamp 55 having an opening 26 (Fig. 2) aligning with open-

2

of the present invention in position to be directed on a sleeping patient.

Fig. 2 is a front elevational view of the health heat lamp shown in Fig. 1.

Fig. 3 is a side elevational view, with parts broken away and shown in section, of the structure illustrated in Figs. 1 and 2.

Fig. 4 is a side view, with parts broken away and shown in section, of an infrared element suitable for use in the health heat lamp of the present invention.

Fig. 5 is a perspective view, with part broken away, of the fiberglass filter shown in dotted outline in Fig. 2.

Fig. 6 is a diagrammatic view of the health heat lamp of the present invention.

Fig. 7 is a sectional view of the lamp.

Fig. 8 is a fragmentary detail view of the inner reflector.

Fig. 9 is a front view of the upper portion of the stand with reflector removed.

Fig. 10 is a rear view of the structure shown in Fig. 9.

Fig. 11 is a front view of the inside of the outer reflector.

Fig. 12 is a fragmentary detail view of an inner reflector clamp.

Fig. 13 is a fragmentary detail view of the clamp shown in Fig. 12 as connecting the inner and outer reflectors.

Fig. 14 is a top plan view of the infrared element.

The health heat lamp has a hollow stand or cabinet 15 shown tubular in shape. It may be made of metal or any other material adapted for such use. The stand 15 has a base 16 adapted to support the stand in upright position.

An ultraviolet, ultra high frequency germicidal lamp 17 is mounted in the stand 15, brackets 18 and 19 being secured to the stand to hold the lamp 17 and for electrical connections to it. A suitable ballast, such as forty watt ballast 20 is provided for the lamp 17 in the base 16, the ballast being removably secured to the base.

The base 16 has an opening 21 (Fig. 2) into the stand 15, the opening 21 being substantially the same size as the inside diameter of the stand. A filter 22 of fiberglass or the like is removably secured over the opening 21 to filter out dust and other foreign particles from air passing through the opening 21.

An outer reflector 23 is pivotally mounted on the stand 15 at the top of the stand. An opening 24 is formed in the reflector and a duct 25 connects the hollow stand with the reflector, duct 25

ing 24 in the reflector. A clamping screw knob 27 engages a threaded stud 28 on the reflector and a slot 29 is provided in the rear side of duct 25 for the stud to pass through so that the screw knob 27 may engage it and bear against the rear side of the duct bridging the slot 29. In this manner, the reflector 23 may be tilted to various angles and secured at those angles. A twenty degree movement, however, has been found to be ample. Protective guard members 30 (Fig. 1) are provided at the face of the reflector.

An infrared or black heat element 31 is mounted in the reflector to produce invisible, nonactinic radiant energy detectable by its thermal effect. Element 31 consists of a stainless steel sheathing 32 (Fig. 3) over a ceramic liner 33 enclosing a helical coil 34 of Nichrome wire. When hot, the element 31 is nonincandescent and emits rays having wave lengths longer than those of visible light and shorter than those of radio waves, the waves emitted being longer than 7600 Angstroms or angstrom units. The element 31 is mounted in an inner reflector 23' by strip brackets 35 which are removably secured to the reflectors, as by screws 36 (see Fig. 2). The space between the two reflectors permits air passage out the front of the reflector 23 in a substantially annular or cone shaped air stream.

A motor 37 is mounted by strap 38 in the casing near the base above the filter 22 and base opening 21 and a fan 39 is secured to the motor shaft to draw air through the filter and base opening and force it up through the stand over the ultraviolet lamp 17 and out duct opening 26 to the reflector 23 where it can be directed by the reflector in any direction desired along with the infrared rays and the sterilized air rays from the element 31 and lamp 17.

A master switch 40 (Fig. 2) is provided on the duct 25 to connect and disconnect the entire unit to and from a source of electrical energy (not shown). A switch 41 is also provided for the infrared element 31 and a switch 42 for the ultraviolet and ultra high frequency lamp 17. Motor switch 43 for the motor 37 completes the bank of switch. All switches are connected with their respective units and with the source of electrical energy.

The forced air drawn in the stand or cabinet by the fan 39 and directed over the ultraviolet germicidal lamp 18 serves to cool the lamp and can be regulated by proper fan speed to keep the lamp at the temperature at which the lamp operates at maximum efficiency. Commercially available tubes operating at a 70° maximum efficiency temperature can be used in the health lamp of the present invention with their best results. The ultra high frequency and the ultraviolet waves will destroy bacteria, germs and other harmful microorganisms which get through the filter 22.

Preferably, ultraviolet lamp 17 is one adapted to emit radiant (nonluminous) energy in waves centering around the range of from 3000 down to 1850 Angstroms or angstrom units and one which produces little or no ozone. The inside of the stand of cabinet 15 adjacent the lamp 17 is sprayed with a specular aluminum lining for a high reflection factor and intensification of the rays.

A medicant or deodorant holding cup 44 may be removably secured to the center of grill members 30 as shown in the first three figures. Preferably the cup is of copper for ready heat evaporation

of the contents by the infrared heater to disperse the contents into the air stream.

Fig. 1 shows the lamp as used at night on a patient alongside of bed 46.

5 While I have illustrated and described the preferred embodiment of my invention, it is to be understood that I do not limit myself to the precise construction herein disclosed and the right is reserved to all changes and modifications 10 coming within the scope of the invention as defined in the appended claims.

Having thus described my invention, what I claim as new, and desire to secure by United States Letters Patent is:

15 1. A health heat lamp comprising a hollow stand and a base for the stand, an ultraviolet lamp, means to mount the lamp in the stand, said base having an opening into the stand, an outer reflector pivotally mounted on the stand, 20 an inner reflector mounted within said outer reflector and spaced therefrom to provide an air channel therebetween, an infrared element mounted in the inner reflector, a motor and fan in the stand to draw air into the stand and force 25 it through the rays of the lamp, said stand and outer reflector having aligned openings for air to enter the air channel and be directed past the infrared element.

2. A health heat lamp comprising a hollow

30 stand and a base for the stand, an ultraviolet lamp, means to mount the lamp in the stand, said base having an opening into the stand, a filter removably secured over the base opening, an outer reflector pivotally mounted on the stand, 35 an inner reflector mounted within said outer reflector and spaced therefrom to provide an annular air channel therebetween, an infrared element mounted in the inner reflector, a motor and fan in the stand to draw air into the stand through the filter and force it through the rays of the lamp, said stand and reflector having aligned openings so that the filtered and sterilized air will enter the air channel and be directed past the infrared element, said infrared element being adapted to emit radiant energy in waves larger than 7600 Angstroms and said ultraviolet lamp being adapted to emit radiant energy in waves centering around the range of from 3000 down to 1850 Angstroms.

3. A health heat lamp comprising a hollow

50 stand and a base for the stand, an ultraviolet lamp, means to mount the lamp in the stand, said base having an opening into the stand, a filter removably secured over the base opening, an outer reflector pivotally mounted on the stand, 55 an inner reflector mounted within said outer reflector and spaced therefrom to provide an annular air channel therebetween, an infrared element mounted in the inner reflector, a motor and fan in the stand to draw air into the stand through the filter and force it through the rays of the lamp, said stand and reflector having aligned openings so that the filtered and sterilized air will enter the air channel and be directed past the infrared element, said infrared element 60 being adapted to emit radiant energy in waves larger than 7600 Angstroms and said ultraviolet lamp being adapted to emit radiant energy in waves centering around the range of from 3000 down to 1850 Angstroms, ballast disposed in the base for the ultraviolet lamp, switches for the lamp, infrared element and motor, means to connect the lamp, element and motor with the switches and means to connect the switches with a source of electrical energy.

4. A health heat lamp comprising a hollow

stand and a base for the stand, an ultraviolet lamp, means to mount the lamp in the stand, said base having an opening into the stand, a filter removably secured over the base opening, an outer reflector pivotally mounted on the stand, an inner reflector mounted within said outer reflector and spaced therefrom to provide an annular air channel therebetween, an infrared element mounted in the inner reflector, a motor and fan in the stand to draw air into the stand through the filter and force it through the rays of the lamp, said stand and reflector having aligned openings so that the filtered and sterilized air will enter the air channel and be directed past the infrared element, said infrared element being adapted to emit radiant energy in waves larger than 7600 Angstroms and said ultraviolet lamp being adapted to emit radiant energy in waves centering around the range of from 3000 down to 1350 Angstroms, ballast disposed in the base for the ultraviolet lamp, switches for the lamp, infrared element and motor, means to connect the lamp, element and motor with the switches and means to connect the switches with a source of electrical energy, said infrared element having a stainless steel sheathing and a ceramic liner with a helical coil of Nichrome wire enclosed therein.

5. A health heat lamp comprising a hollow stand and a base for the stand, an ultraviolet lamp, means to mount the lamp in the stand, said base having an opening into the stand, a filter removably secured over the base opening, an outer reflector pivotally mounted on the stand, an inner reflector mounted within said outer 35

reflector and spaced therefrom to provide an annular air channel therebetween, an infrared element mounted in the inner reflector, a motor and fan in the stand to draw air into the stand through the filter and force it through the rays of the lamp, said stand and reflector having aligned openings so that the filtered and sterilized air will enter the air channel and be directed past the infrared element, said infrared element being adapted to emit radiant energy in waves larger than 7600 Angstroms and said ultraviolet lamp being adapted to emit radiant energy in waves centering around the range of from 3000 down to 1350 Angstroms, ballast disposed in the base for the ultraviolet lamp, switches for the lamp, infrared element and motor, means to connect the lamp, element and motor with the switches and means to connect the switches with a source of electrical energy, said infrared element having a stainless steel sheathing and a ceramic liner with a helical coil of Nichrome wire enclosed therein, said ultraviolet lamp being an ultra high frequency tube.
